UNITED STATES PATENT OFFICE

127,783

DESIGN FOR A COMBINED HOOD AND SUPPORTING UNIT FOR GAS INSTALLATION HOUSINGS

Peter A. Anderson, Portland, Maine, assignor to Utilities Distributors, Inc., Portland, Maine, a corporation of Maine

Application February 15, 1941, Serial No. 99,026

Term of patent 14 years

To all whom it may concern:

Be it known that Peter A. Anderson, a citizen of the United States, residing at Portland, in the county of Cumberland and State of Maine, has invented a new, original, and ornamental Design for a Combined Hood and Supporting Unit for Gas Installation Housings, of which the following is a specification, reference being had to the accompanying drawing, forming part thereof, wherein:

Figure 1 is a perspective view of a combined hood and supporting unit for gas installation housings showing my new design.

Figure 2 is a front elevation of the same.

Figure 3 is a top plan view.

I claim:

The ornamental design for a combined hood and supporting unit for gas installation housings, as shown.

PETER A. ANDERSON.
